Fig. 5

FIG. 1 is a top plan view of a golf tee shelter, showing my new design.

FIG. 2 is a front elevational view.

FIG. 3 is a side elevational view of the shelter with the tubular base member being broken away to indicate indeterminate length;

FIG. 4 is a rear elevational view; and

FIG. 5 is a vertical sectional view taken along the line 5-5 in FIG. 2.

The tubular base member is shown broken away in FIGS. 2, 4 and 5 for convenience of illustration.

I claim:

The ornamental design for a golf tee shelter, as shown and described.
